UNITED STATES PATENT OFFICE.

JACOB BAAS, OF DARMSTADT, GERMANY.

LIFT.

1,107,739.

Specification of Letters Patent. Patented Aug, 18, 1914.

Application filed March 12, 1912. Serial No. 683,260.

To all whom it may concern:

Be it known that I, JACOB BAAS, manufacturer, a subject of the German Emperor, and resident of Darmstadt, Grand Duchy of Hesse, Germany, with the post-office address Riegerplatz 11, have invented new and useful Improvements in Lifts, of which the following is a specification.

The present invention relates to elevators or lifts, and has for its object to provide a novel form of elevator adapted to carry freight or passengers to and from different floors of a building or structure, and also to convey the persons or goods to be transported to and from different points on the several floors.

To this end, the invention comprises an outer cage or elevator car mounted to operate in a vertical shaft, within which is mounted an inner cage or car capable of a limited vertical movement within the outer car, and normally supported in said outer car by means of the hoisting cable which serves to raise and lower both cars, said inner cage being also adapted to be lowered upon a tiltable platform or bottom carried by the outer car, from which the inner car may be moved from the outer car in a horizontal direction and on to the floor adjacent which the elevator has been stopped, upon which floor the said inner car may be guided or directed to any desired location, either to discharge or take on goods or passengers, after which the said inner car is drawn back by the hoisting cable along the floor, thence into the outer car, and the two cars raised or lowered in the vertical elevator shaft. Incidentally, the invention also contemplates the provision of electrical stop devices, which serve to arrest and support the outer car at any one of the several floors, as will be hereinafter explained.

The invention is illustrated in the accompanying drawings, in which:—

Figure 1 is a diagrammatic view illustrating so much of the installation as is necessary for a complete understanding of the invention; and Fig. 2 is a detail view, partly in vertical section, showing the rotatable inclined floor of the outer cage.

Referring to the drawings, *a* indicates the hoisting drum, which may be of any ordinary type which operates the cable or rope *b*, which latter passes over an overhead pulley or sheave *z* and is connected to the inner

cage *c*, in any appropriate manner. Said inner cage *c* is mounted for limited vertical movement in an outer cage *d*, which latter is preferably guided at its corners in the ordinary vertical well or shaft, so as to leave all four sides of the shaft, at the floor levels, free and unobstructed. The outer cage *d* is provided with a rotatable inclined bottom *e*, which may be conveniently constructed in the manner illustrated in Fig. 2, to permit said bottom to be turned, so as to present the incline thereof toward any of the sides of the elevator well at the various floors.

At each floor level, there are mounted on opposite sides of the elevator well, pivoted stop lugs *i*, which are normally retracted by counter-weights *k* to inoperative position to permit the elevator to move in either direction, as indicated in the lower part of Fig. 1. The stops *i* are moved into operative position below the cage *d* to support the latter, under proper conditions, at any desired floor, by means of electro-magnets *g*, one for each set of stops, the pivoted armature of each magnet being connected to the corresponding stops by means of links *h*, which serve to rock the stops on their pivots, so that the forward ends project into the elevator well under the bottom of cage *d*, when the corresponding magnet is energized. As soon as the cage is lifted to disengage the stops *i*, the latter are rocked to inoperative position by the counter-weights *k*. Obviously, the magnets *g* may be controlled by any appropriate means, such, for example, as by ordinary push buttons, to arrest and support the elevator cage *d*, at any desired floor level.

The operation of the apparatus as thus described, is as follows: When the elevator, consisting of the two cages *c* and *d*, is raised by the hoisting cable to any desired floor, the upward movement of the outer cage is continued for a short distance above the desired floor level and during the ascending movement, all of the magnets being deenergized, the various stops *i* are in normally retracted position and do not interfere with the movement of the outer cage. After the latter has been raised a slight distance above the desired floor level, the magnet *g*, which controls the stops at that particular floor level, is energized and moves the stops, so that the inner ends thereof project into the well and into position shown in the upper

portion of Fig. 4. The winding drum is then reversed, and the outer cage permitted to descend until the bottom thereof rests upon the inner ends of the stops *i*, which latter support the outer cage at the desired floor level. After the outer cage is brought to rest upon the stops, the energizing current through the corresponding magnet *g* may be interrupted to prevent waste. The continued unwinding of the cable *b* from the drum *a* permits the inner cage *c* to descend a short distance within the outer cage until said inner cage rests upon the inclined bottom *e* of the outer cage, down which bottom the inner cage rolls and passes out of the outer cage and on to the floor adjacent to which the elevator has been stopped. The inner cage may then be rolled either over the floor or upon appropriate tracks provided therefor, to any desired portion of the floor, where it is either loaded or unloaded, and is then drawn back into the outer cage along the floor or tracks, when the hoisting cable is taken up by the drum *a*. After the inner cage *c* passes into the outer cage *d*, the continued lifting movement of the cable causes the inner cage to rise within the outer cage until both cages are lifted. When the outer cage is lifted sufficiently to disengage the stops *i*, the latter are automatically retracted by their counter-weights *k*, and both cages may be raised or lowered, as desired. As hereinafter indicated, the inclined bottom *e* is adapted to be rotated so as to permit the inner cage to pass from the outer cage on to the desired floor, in any direction, and when the floors are provided with tracks, to receive and guide the inner cage, in its movement over the floor, said tracks are preferably inclined to facilitate the automatic movement of the cage outward over the floor, and said tracks may, if desired, be

provided with stops to arrest the movement of the inner car wherever desired.

It will be understood, of course, that the hoisting mechanism of the elevator may be of any appropriate form, and may be controlled by any of the ordinary apparatus provided for that purpose, mounted either on the elevator car proper, or at the various floor levels, or, in the alternative, at some central control station.

What I claim is:

1. In a lift, an inner cage, a hoisting rope connected with the inner cage passing over a guide sheave at the top of the well and connected with a hoisting drum, and an outer cage provided with an inclined bottom to permit the inner cage to be moved out of the outer cage and onto the adjacent floor.

2. In a lift, an inner cage, a hoisting rope connected with the inner cage passing over a guide sheave at the top of the well and connected with a hoisting drum, an outer cage having an inclined bottom carrying the inner cage and an electromagnetically controlled supporting device for the outer cage.

3. In an elevator mechanism, an inner cage, a hoisting cable engaging an overhead guide sheave connected therewith, an outer cage in which said inner cage is supported for independent movement, and means for supporting the outer cage at a desired floor to permit the inner cage to be moved out of said outer cage and onto said floor.

In testimony, that I claim the foregoing as my invention, I have signed my name in presence of two witnesses, this first day of March 1912.

JACOB BAAS.
